[57] CLAIM

The ornamental design for a lavatory, as shown and described.

DESCRIPTION

FIG. 1 is a perspective view taken from the top, front and right side of a lavatory embodying our new design;

FIG. 2 is a top plan view thereof;

FIG. 3 is a cross-sectional view taken on line 3—3 of

FIG. 2; and,

FIG. 4 is a cross-sectional view taken on line 4—4 of

FIG. 2.

The fragmentary broken line representation of a counter top in FIG. 1 and the broken line representations of mounting holes in FIGS. 1 and 2 are for purposes of illustration only and form no part of the claimed design.

FIG. 1

FIG. 2

FIG. 3

FIG. 4
